UNITED STATES PATENT OFFICE.

CHESTER H. THORDARSON, OF CHICAGO, ILLINOIS.

TRANSFORMER AND LIKE COILS.

1,255,947.

Specification of Letters Patent. Patented Feb. 12, 1918.

Application filed December 8, 1913, Serial No. 805,252. Renewed July 23, 1917. Serial No. 182,358.

To all whom it may concern:

Be it known that I, CHESTER H. THORDARSON, a citizen of the United States, and a resident of Chicago, in the county of Cook

5 and State of Illinois, have invented certain new and useful Improvements in Transformers and like Coils; and I do hereby declare that the following is a full, clear, and exact description thereof, reference being 10 had to the accompanying drawings, and to the characters of reference marked thereon, which form a part of this specification.

This invention relates to coil structures for transformers and like uses. The invention 15 has for its object to provide means for maintaining the elements of the coil structure in proper position with relation to each other and to the insulation interposed between the elements.

20 In transformers and like electrical devices the pressure of the current passing through the windings of the coil tends to cause the coil elements to separate one from the other by reason of the potential difference between adjacent coil elements. In

25 the case of simple windings the turns of the coil tend to thus separate, and, in the case of windings made up of a plurality of separate winding sections suitably connected, there is a tendency for the section to spread apart by the pressure due to the potential difference between the winding sections.

In a transformer and like electrical devices the magnetic flux of the primary circuit exerts a mechanical pressure on the closed secondary windings that has an effect of not only pushing the secondary windings away from the primary but also in spreading apart the different turns of the secondary.

40 and the magnetic flux of the primary circuit sets up with every wave a pulsation or mechanical strain in every turn of its own circuit and similarly in the secondary. All the electrical conductors in the transformer, both the primary and the secondary, while in operation are under a continuous vibratory strain. This has a tendency to loosen the insulation and, especially when the insulation becomes hot, it has 45 a tendency to make it yield.

If a lateral spring pressure is applied on the whole mass of conductors it has the effect of compressing and re-setting all conductors in a closer and more stable position and, at the same time, preventing any solid 55 insulation from yielding, crumbling or

wearing away. In any event, the repeated displacement of the coil elements and insulation has the effect to break down or impair the efficiency of the insulation between 60 said elements and thereby render the coil subject to short circuits.

In accordance with my invention I propose to provide means for exerting a constant resetting pressure against the coil 65 elements which operates, after the separating pressure referred to has subsided, to at once restore the elements to their normal or original positions. The said resetting means are yielding means and may 70 consist of springs interposed between the coil elements and fixed parts of the frame supporting or surrounding the coil structure.

My improvements are more particularly adapted to the type of winding structure 75 illustrated in my co-pending application for U. S. Letters Patent, Serial No. 776,521 filed on the 30th day of June, 1913, and applied, as herein shown, to the secondary or high tension winding, wherein the winding consists of a plurality of winding units, each composed of a flat spirally wound wire with the turns suitably insulated, and with the several units suitably connected together. Said improvements are especially adapted 80 to this type of winding, inasmuch as the resetting pressure may be applied to the winding in directions which do not tend to crush the winding structure, and which does not disarrange the turns relatively to each 85 other.

In the drawings:—

Figure 1 is a central vertical section, on the line 1—1 of Fig. 2, of a transformer provided with my improvements.

Fig. 2 is a plan view of a transformer, with parts broken away.

Fig. 3 is a transverse section on the line 3—3 of Fig. 2.

Fig. 4 is a horizontal section, on a smaller 100 scale, showing also the casing inclosing the transformer elements, and also showing an additional arrangement of the resetting means.

As shown in the drawings, 10 designates 105 the core member, 11, 12 the top and bottom members and 13 the end members of the magnetic circuit of a shell type transformer to which my invention is herein shown as applied, though not limited thereto. The 110 said magnetic circuit is composed of thin laminæ clamped or confined together in

any suitable manner, as by the side plates 14, 14 arranged along the upper and lower longitudinal marginal portions of the magnetic circuit, and bolts 15, 15 extending through the said plates beyond the ends of the magnetic circuit. The said plates 14 are provided with lateral flanges 16 through which extend spacing bolts 17 which space the clamping plates, said bolts being screw-threaded at their ends to receive clamping nuts which engage the upper and lower faces of the flanges, as indicated in Fig. 1. The said magnetic circuit may be divided into sections, separated by spaces 18 for the passage of a cooling medium whereby to ventilate the core.

The said circuit is provided with the usual windows 20, 20 on opposite sides of the central core member 10, through which the sides or legs of the primary and secondary windings, designated as a whole by 22, 23, respectively, extend. The said primary winding may be of any suitable type and is separated from the core member by an insulating ring or sleeve 25, and the turns of the said primary winding are insulated by the insulating members 26.

The secondary winding, as herein shown, is made up of a plurality of independently wound sections 28, each composed of a flat conductor strip or wire wound spirally about the axis of the section to produce open flat, disk-like sections such, for instance, as is shown in my aforesaid co-pending application for U. S. Letters Patent. The said winding sections are produced by spirally winding a flat wire the required number of turns with an insulating medium between the turns thereof, the insulating medium being so arranged as to expose the bare edges of each turn of each winding section. In the type of transformer herein shown the secondary coil surrounds the primary coil but the coils may be otherwise arranged in inductive relation to each other. The said winding sections may be connected together either in series or in multiple, and it has not been deemed necessary to show these connections, nor the terminals leading from the transformer, such connections and terminals being of any arrangement suitable to the particular type of transformer to which the invention may be applied.

Referring now more particularly to the application of my invention to the type of transformer herein described, it will be noted, first, that the resetting means referred to are applied to maintain a constant and yielding pressure against the winding sections in a manner to hold them grouped or compact, as best shown in Figs. 1, 2 and 3, and also to hold the turns of the windings of the several sections in like manner pressed one upon the other, as exemplified in Fig. 4.

Referring to the construction shown in

Figs. 1, 2 and 3, it will be seen that the several sections of the secondary winding are separated by insulating pieces or blocks 30. These blocks are preferably elongated and extend across the sides or legs of the sections so as to constitute bracing pieces. The bracing function is especially useful when employed with winding sections made up as herein shown, inasmuch as a localized pressure on the flat sides of the sections acting against an area less than the width of the legs thereof would tend to relative displacement of the turns and a consequent deformation of the sections. Said blocks also serve to incidentally divide the spaces between the sections into a plurality of lateral passages for the traverse of a cooling medium by which to ventilate the coil.

The coil sections with their interposed insulations are pressed together between upper and lower abutments carried by the frame. The abutments at one side of the coil structure may be fixed and at the other side spring pressed and adjustable. As herein shown, the abutments at both sides of the coil structure are spring pressed and adjustable. They consist of pins or posts 35, 36 which engage the upper and bottom-most insulating strips or blocks 30, the posts 35 being associated with the sides or legs of the winding sections at the sides of the magnetic circuit, and the posts 36 being associated with the legs of the winding sections which extend through the magnetic circuit. The said posts 36, as herein shown, are reduced and extend through the ventilating spaces 18 of the magnetic circuit for engagement with the insulating blocks 30.

The posts 35, associated with the legs or sides of the winding sections at the lateral sides of the magnetic circuit are arranged in pairs, and the posts of each pair are borne upon by the ends of a curved spring 39, arranged between the posts and the lateral flange 16 of the adjacent clamping plate 14. In order to adjust the force of said springs they are borne upon at their outer curved portions by adjusting screws 40 which extend through and have screw-threaded engagement with the flanges 16. The posts 36 are likewise arranged in pairs and bear against the ends of curved springs 41 which latter, in turn, bear at their central curved portions against adjusting screws 42 that pass through and have screw-threaded engagement with U-shaped members 43, 43 of coil frames that extend transversely across the ends of the magnetic circuit and are attached to the flanges 16 by bolts 45. The employment of the adjusting screws 40 and 42 permits the pressure exerted by the springs, through said posts, against the winding sections to be varied.

With the construction described, the exertion of a separating pressure, tending to sep-

erate or spread the sections of the coil when current is flowing therethrough, is yieldingly opposed by the springs. When the separating pressure ceases the springs will 5 return or reset the coil sections to their original positions relatively to each other and to the insulation, whereby efficiency of the coil is not impaired.

In Fig. 4, I have shown, in addition to the 10 resetting features of the previously described construction, means acting radially against the turns of the separate winding sections to maintain the turns of the winding sections and the insulation between 15 the turns in a like relative position by resetting the displaced turns upon the occasion of separation under pressure. This may be effected in various ways. I have herein shown a simple method which consists of the 20 interposition of spiral springs 50 between the casing 51 which incloses the transformer elements and strips 52, 52 which extend across the outer edges of the winding sections, said strips being made of any suitable 25 insulating material. These springs act with a yielding pressure against the strips 52, which in turn act against the turns of the winding from all directions. These springs yield to slight separation of the winding 30 when a heavy current is passing through the same, and reset the turns or return them to their original positions when the separating pressure ceases. The said springs may also be provided with the adjusting means illus- 35 trated in the previously described construction for adjustably varying the pressure of the springs against the coil elements.

The arrangement of the spacer members 30 in the relation, as shown, between and 40 against the sides of the coils is particularly advantageous with respect to the yielding or spring-like connection between the fixed parts of the transformer structure and the winding sections, inasmuch as said arrangement provides means for bracing the winding sections and holding them with their turns in proper relation. It will be noted 45 that the winding sections are not supported by taping as is usual in transformer constructions and the particular arrangement of the yieldingly held spacer members and the winding sections is such as to render taping or other means of bracing the winding sections unnecessary.

55 From the foregoing disclosure it will be evident that my improvements may assume wide variation within the spirit and scope of the invention, and the invention is not limited to the structural details shown except as hereinafter made the subject of specific claims.

It will be noted that the resetting spring pressure as applied to all the constructions shown in all the figures operates to avoid 60 crushing pressure against the winding turns

in a manner to disarrange the turns relatively to each other and to the insulation. In the construction shown in Figs. 1, 2 and 3 the resetting pressure is exerted edgewise of the turns of the flat wire, while in the construction shown in Fig. 4 the resetting pressure is exerted in a direction transverse to the planes of the turns of the flat wire. Thus, the resetting pressure does not tend to crush the turns of the winding in a manner to disarrange the relation of the turns to each other and to the insulation between the same and between the winding and the magnetic circuit. However, it will be noted, with respect to the construction shown in Figs. 80 1, 2 and 3 that the insulating strips 30, through which the resetting pressure is exerted on the winding units constitutes means for directing a cooling medium to the bare edges of the turns of the winding units, so 85 that said strips serve as a means for transmitting the resetting pressure, to brace the winding units, and to direct a cooling medium, as oil, across the faces of said units.

I claim as my invention:—

1. In a transformer, a core member, a frame associated therewith, the primary and secondary winding sections arranged in inductive relation to each other and to the core member, the secondary winding being composed of a plurality of disk-like sections each made of a spirally wound flat wire with the turns insulated from each other, spacing members between said sections and yielding means interposed between the frame and the 95 group of secondary winding sections constructed to exert a constant yielding pressure against said sections in edgewise relation to said turns and in a plane transverse to the planes of the sections.

2. In a transformer, a core member, a frame associated therewith, the primary and secondary winding sections arranged in inductive relation to each other and to the core member, the secondary winding being 100 composed of a plurality of disk-like sections each made of a spirally wound flat wire with the turns insulated from each other, narrow spacing members extending across the flat faces of the disk-like winding sections and transversely of the edges of the turns, said spacing members being arranged in groups with the members of each group in line with each other and yielding pressure means interposed between the frame and the outermost spacing members of each group.

3. In a transformer, a core member, a frame associated therewith, the primary and secondary winding sections arranged in inductive relation to each other and to the 115 core member, the secondary winding being composed of a plurality of disk-like sections each made of a spirally wound flat wire with the turns insulated from each other, relatively narrow spacing members extending 120 125 130 135 140 145 150 155 160 165 170 175 180

across the flat faces of the disk-like winding sections and transversely of the edges of the turns, said spacing members being arranged in groups with the members of each group in line with each other and yielding pressure means interposed between the frame and the outermost spacing members of each group, and acting against the edges of said turns and transversely to the plane of the sections, said spacing members being spaced from each other to afford ventilating passages radially through the secondary winding.

4. In an electro-magnetic device, a winding composed of a plurality of connected disk-like or slab units, each consisting of a spirally wound flat wire, insulated between the turns thereof, and yielding resetting means acting edgewise against said turns and transversely to the planes of the units.

5. In an electro-magnetic device, a winding composed of a plurality of connected disk-like or slab units, each consisting of a spirally wound flat wire, insulated between the turns thereof, yielding resetting means acting edgewise against said turns and other

resetting means acting flatwise against said flat wire turns.

6. In an electro-magnetic device, a winding composed of a plurality of connected disk-like or slab units, each consisting of a spirally wound flat wire, insulated between the turns thereof, and yielding resetting means acting against said turns in a direction to avoid crushing said turns to disarrange them relatively to each other and to the insulation between the same.

7. In an electro-magnetic device, a winding composed of a plurality of connected disk-like or slab units, each consisting of a spirally wound flat wire, the turns of which are disposed parallel to the axes of the units, insulated between the turns thereof, and yielding resetting means acting flatwise against said flat wire turns.

In testimony, that I claim the foregoing as my invention I affix my signature in the presence of two witnesses, this 3rd day of December, A. D. 1913.

CHESTER H. THORDARSON.
